(57) **CLAIM**

The ornamental design for a wig grip band, as shown and described.

DESCRIPTION

FIG. 1 is a front perspective view of a first embodiment of a wig grip band, showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a further front perspective view thereof, wherein the wig grip band is shown deployed on the head of a wearer;
FIG. 9 is a further front view thereof, wherein the wig grip band is shown deployed on the head of a wearer;
FIG. 10 is a further rear view thereof, wherein the wig grip band is shown deployed on the head of a wearer;
FIG. 11 is a further left side view thereof, wherein the wig grip band is shown deployed on the head of a wearer;
FIG. 12 is a further right side view thereof, wherein the wig grip band is shown deployed on the head of a wearer;
FIG. 13 is a further top view thereof, wherein the wig grip band is shown deployed on the head of a wearer;
FIG. 14 is a further bottom view thereof, wherein the wig grip band is shown deployed on the head of a wearer;
FIG. 15 is a front perspective view of a second embodiment of a wig grip band, showing my new design;
FIG. 16 is a front elevational view thereof;
FIG. 17 is a rear elevational view thereof;
FIG. 18 is a left side elevational view thereof;
FIG. 19 is a right side elevational view thereof;
FIG. 20 is a top plan view thereof;
FIG. 21 is a bottom plan view thereof;
FIG. 22 is a further front perspective view thereof, wherein the wig grip band is shown deployed on the head of a wearer;
FIG. 23 is a further front view thereof, wherein the wig grip band is shown deployed on the head of a wearer;

(Continued)

FIG. 24 is a further rear view thereof, wherein the wig grip band is shown deployed on the head of a wearer; FIG. 25 is a further left side view thereof, wherein the wig grip band is shown deployed on the head of a wearer; FIG. 26 is a further right side view thereof, wherein the wig grip band is shown deployed on the head of a wearer; FIG. 27 is a further top view thereof, wherein the wig grip band is shown deployed on the head of a wearer; and, FIG. 28 is a further bottom view thereof, wherein the wig grip band is shown deployed on the head of a wearer. The broken lines in FIGS. 1-28 are for the purpose of illustrating portions of the wig grip band and environmental structure that form no part of the claimed design.
